UNITED STATES PATENT OFFICE.

WILLIAM CARNEY AND FREDERICK C. CHASE, OF FREDERICKSBURG, IOWA.

COMBINATION-SQUARE.

1,258,985.

Specification of Letters Patent. Patented Mar. 12, 1918.

Application filed July 31, 1915. Serial No. 42,876.

To all whom it may concern:

Be it known that we, WILLIAM CARNEY and FREDERICK C. CHASE, citizens of the United States, residing at Fredericksburg, 5 in the county of Chickasaw and State of Iowa, have invented certain new and useful Improvements in Combination-Squares, of which the following is a specification.

This invention relates to carpenters' tools, 10 particularly to squares, and has for its object the provision of a novel square whereby the side and plumb cuts may be marked on any common, hip, valley, jack or "cripple" rafter with ease and accuracy, two blades 15 being provided and actuated by arms movable over scales graduated in the rise in inches per foot run.

An important object is the provision of a device of this character in which the blades 20 may be moved to and held at an intermediate position for squaring timbers, and in which the blades may be moved and adjusted in either direction to facilitate the use of the tool by either right or left handed 25 persons.

The most essential object is the provision of a square of this character in which the arms and blades are independently movable so that in case runs are uneven the blades 30 for marking the side and plumb cuts may be adjusted at different angles.

Another object is the provision of a movable plate upon which one of the blades is pivoted whereby the lines marked may be 35 caused to intersect at certain angles, three stops being provided for the sliding plate, the extreme stops being for positioning the blade when both blades are at an angle, and the intermediate one being for positioning 40 the blade when a square cut is to be marked.

A further object is the provision of a tool of this character which will be simple in use, efficient in service, inexpensive and durable, and which may be used by those 45 skilled in the use of instruments of precision.

With these and other objects and advantages in view, the invention consists in the novel construction, arrangement and 50 combination of parts to be hereinafter more fully described, and illustrated in the accompanying drawings, in which:

Figure 1 is a front elevation of the device in position upon a timber to be marked, 55 Fig. 2 is a top plan view thereof,

Fig. 3 is a longitudinal sectional view on the line 3—3 of Fig. 2, and

Fig. 4 is a cross sectional view on the line 4—4 of Fig. 1.

Referring more particularly to the drawings, the numeral 1 designates the body portion or frame of the device, which is formed of metal and which comprises two plates 2 and 3 extending at right angles. The plate 2 terminates at one end in a reduced extension 4, while the other plate 3 is cut away, as shown at 5, at its corresponding end. The plate 2 is provided with a longitudinal slot 6 and with a cut-out portion 7 for a purpose to be described. Pivotaly mounted 60 upon the reduced extension 4, as shown at 8, is a blade 9 which may be swung in either direction. An arm 10 is pivotally connected with the blade 9, as shown at 11, and is apertured at its free end for the passage of 65 a bolt 12 which is slidable in the slot 6 and which carries a clamping nut 13. A scale 14 is marked upon the plate 2 and has its graduations ranging from 0 at its center to 16 at its ends, each graduation representing 70 a rise of one inch per foot run.

The plate 3 of the body portion is provided with a slot 15 extending longitudinally thereof and is further provided adjacent its cut-away ends 5 with guide rivets 85 16 which extend through slots 17 in a plate 18 slidable longitudinally upon the body plate 3. A strip 19 of spring metal is disposed upon the plate 18 and is provided with a slot 20 registering with one of the 90 slots 17. A locking screw 21 passes through aligned openings in the plate 18 and spring strip 19, and is engageable within a selected one of three threaded openings 22, 23, and 24 in the plate 3. The plate 18 and strip 19 95 may thus be moved into and held in any desired one of three positions for a purpose which will become apparent hereinafter. A blade 25 is pivotally connected, as shown at 26, with the outer ends of the plate 18 and strip 19. An arm 27 is pivotally connected, 100 as shown at 28, with the blade 25, and is apertured at its free end for the passage of a bolt 29 slidable within the slot 15 and carrying a clamping nut 30. A scale 31 exactly 105 similar to the scale 14 is marked upon the plate 3. Both the arms 10 and 27 are provided upon their inner ends with projecting points 32 positioned to be movable over the scales 14 and 31, respectively.

In the use of the device, when it is desired to mark a timber for squaring it, the plate 18 is disposed in its intermediate position, as clearly shown in Fig. 2, with the 5 screw 21 engaged within the threaded opening 23, and both arms 10 and 27 are moved until the points 32 indicate 0 on both the scales 14 and 31. The blades 9 and 25 will then extend at right angles to the edge of 10 the timber and to each other. A line drawn along the edge of these blades will mark the side and plumb cuts for making a square end.

When it is desired to mark a rafter with 15 the side and plumb cuts necessary for a roof of a certain pitch, where the pitches are equal, it is merely necessary to slide the arms 10 and 27 along the body 1 until the points 32 indicate the proper graduations 20 of the rise in inches per foot run upon the scales 14 and 31, the graduations corresponding. Before this is done, however, the plate 18 and strip 19 should be moved either outwardly or inwardly to conform to the 25 right or left rafter, the screw 21 being then engaged in either the threaded opening 22 or the opening 24, as the case may be. The blades 9 and 25 being thus positioned, a line drawn upon a rafter along their edges will 30 give the proper marking for the necessary cuts.

When the pitches of a roof are uneven, the arm 27 is moved until it indicates the proper graduation to give the correct angle 35 to the blade 25, and the arm 10 is moved until it indicates the proper graduation to position the blade 9 at the other proper angle. The marks are then made as in the previous instances. It is, of course, understood that the clamping nuts 13 and 30 are 40 tightened when the blades have been properly adjusted, so as to prevent undesired movement thereof.

As the scales run both ways from 0 it will 45 be readily seen that the device may be used from either the right or left side with equal ease. By setting both arms 10 and 27 to indicate 0, the device may be used as a try-square and by setting the blades 9 and 25 at the correct angles, it may be used as a bevel-square or miter-square.

The blades 9 and 25 may also be provided at arbitrary intervals, such as one-half inch, with holes 33. By shifting the blades 9 and 55 25 to the desired position and inserting a pencil point within a desired one of the holes 33, and moving the entire device along a beam or board, the effect of a marking gage is produced. After the nut 13 or 30 is 60 loosened, a pencil point may be inserted in the proper one of the holes 13 and the arc of a circle be struck by swinging the blade.

From the foregoing description and a 65 study of the drawings, it will be apparent that there has thus been provided a novel

and efficient tool or instrument whereby rafters, beams, and the like may be accurately marked at certain angles and whereby various other purposes may be accomplished.

It will be readily understood that the 70 right is reserved to make such changes in the form, construction, and arrangement of parts, as will come within the scope of the following claims.

Having thus described our invention what 75 we claim as new and desire to secure by Letters Patent is:—

1. A device of the character described, comprising a body portion, a pair of blades pivotally connected therewith and disposed 80 in planes at an angle to each other, and an arm pivotally connected with each blade and slidably connected with said body portion, said body portion being provided with graduations traveled over by said arms, and 85 means whereby the pivotal connection of one of said blades may be moved longitudinally upon said body portion.

2. A device of the character described, comprising a body portion, a blade pivotally 90 connected therewith, a plate slidable upon said body portion, a second blade pivotally connected with said plate and extending in a plane at right angles to said first named blade and an arm pivotally connected with 95 each of said blades and slidably connected with said body portion, said body portion being provided with graduations traveled over by said arms.

3. A device of the character described, 100 comprising a body portion right-angular in cross-section, a blade pivoted upon one face of said body portion, a plate slidable upon the other face of said body portion, means for securing said slidable plate in a selected 105 position upon said body portion, a blade pivotally connected with said slidable plate and extending in a plane at right angles to the plane of said first named blade, and an arm pivotally connected with each blade 110 and slidably connected with the corresponding face of said body portion, said body portion being provided with graduated scales traveled over by the ends of said arms.

4. A device of the character described, 115 comprising a body portion formed of two sections extending in planes at right angles to each other, a reduced extension formed at one end of one of said sections, the corresponding end of the other section being 120 cut-away, a blade pivoted upon said extension, a plate slidable longitudinally upon said body portion and disposed over the cut-away portion thereof, means for securing said slidable plate at a selected position, a 125 blade pivoted upon said slidable plate and extending in a plane at right angles to the plane of said first named blade, and an arm pivotally connected with each blade and slidably connected with said body portion 130

whereby the angular positions of said blades may be varied, both faces of said body portion being provided with graduations traveled over by the inner ends of said arms.

- 5 5. A device of the character described comprising a body portion formed of two sections extending in planes at an angle to each other, a blade pivoted upon one end of one of said sections, a plate slidable upon 10 the corresponding end of the other section and provided with guide slots, pins extending from said body portion and extending into said slots, means for clamping said plate at a selected position, a blade pivoted 15 upon said plate, and an arm pivotally connected with each blade and the associated section of said body portion, said body portion being provided with graduations traveled over by said arms.
- 20 6. A device of the character described, comprising a body portion formed of two sections extending in planes at right angles

to each other, a blade pivotally connected with one end of one of said sections, a plate slidable upon the corresponding end of the other section, means for guiding said plate upon said second named section, said second named section being provided with a plurality of holes beneath said plate, a screw passing through said plate and engageable 30 within a selected one of said holes, a blade pivotally connected with said plate, and an arm pivotally connected with each of said blades and slidably connected with the adjacent section, said section being provided 35 with graduations traveled over by said arms.

In testimony whereof we affix our signatures in the presence of two witnesses.
